UNITED STATES PATENT OFFICE.

CHARLES TURNER AND RICHARD F. SCHROEDER, OF CHICAGO, ILLINOIS, ASSIGNEES
OF THREE-FOURTHS TO SAID CHARLES TURNER AND ONE-FOURTH TO SAID RICH-
ARD F. SCHROEDER, BOTH OF CHICAGO, ILLINOIS.

OIL-EXTRACTING APPARATUS.

985,863.

Specification of Letters Patent. Patented Mar. 7, 1911.

Application filed January 31, 1910. Serial No. 541,203.

To all whom it may concern:

Be it known that we, CHARLES TURNER and RICHARD F. SCHROEDER, citizens of the United States, and residents of Chicago, county of Cook, and State of Illinois, have invented certain new and useful Improvements in Oil-Extracting Apparatus, of which the following is a specification, and which are illustrated in the accompanying drawings, forming a part thereof.

The invention relates to devices for extracting oils from solids, such as meats, fish, garbage, etc.; its object being to provide for rapid and continuous action upon the material from which the oil is to be extracted by means of a solvent and from which the solvent taken up by absorption may be recovered, and it consists in a structure such as is hereinafter described and as illustrated in the accompanying drawings, in which—

Figure 1 is a perspective view of the machine, a portion being broken away, showing the internal construction; Fig. 2 found in part upon each of two sheets of the drawings, is a longitudinal, vertical section; Fig. 3 is a vertical section on the line 3—3 of Fig. 2; Fig. 4 is a sectional detail of a portion of a pipe or cylinder through which the solid material is passed for treatment, and showing the arrangement of pipes for introducing a dissolving agent; Fig. 5 is a sectional detail of a retarding device which may be mounted within the cylinder; and Fig. 6 is a detail of the delivery end of the cylinder showing a modified form of construction.

The device comprises, generally speaking, a cylinder here shown as horizontal throughout its entire length, and through which the material is driven by means of screw conveyors; a receptacle for the oil liberated by the dissolving agent, that section of the cylinder located within the receptacle being perforated; means for introducing a solvent, such as gasoline, into the material when occupying the perforated section of the cylinder; means for introducing a vaporizing agent, such as steam, into the material after it has passed beyond the receptacle, the portion of the cylinder then occupied by the material being perforated to permit the escape of the vapors and liquids; sectional screw

conveyors revolving within the cylinder for advancing the material therethrough and impacting it at either side of the sections of the cylinder within which it is acted upon by the solvent and the vaporizing agent; and means for introducing into the cylinder these agents; together with other incidental features as hereinafter pointed out.

The cylinder, through which the material to be acted upon is passed, is as a whole designated 10. Adjacent one end thereof there is provided a hopper 11, for receiving the material, and adjacent its opposite end there is provided a discharge nipple 12. A shaft 13 extends entirely through the cylinder and is located upon the axis thereof and is suitably journaled in end plates 14, 15, and carries a pulley 16 by means of which it may be turned. A spiral or screw conveyor 17 is mounted upon the shaft 13 and extends under the hopper 11, and terminates a little short of the section 18 of the cylinder within which the material is acted upon by the solvent, this latter section being located within a tank 19 for receiving the liquids drained off. A second spiral or screw conveyor 20, fixed upon the shaft 13, is located within the section 18 of the cylinder, and moves the material therethrough, delivering it to a third section 21 of the cylinder within which it is to be treated by the vaporizing agent, this section being located within a tank 22. The material is then taken up and advanced by a third spiral or screw conveyor 23 and moved to the discharge end 24 of the cylinder, where it is delivered to the nipple 12. The sections 18 and 21 of the cylinder 10 are freely perforated to permit the escape of vapors and liquids.

The dissolving agent, such as gasoline, is introduced into the section 18 of the cylinder, by means of a pipe 25 leading from a suitable source of supply and entering the tank 19 through branches 26, 27 provided with suitable valves, as indicated at 28, 29, these branch pipes each communicating with pipes as 30, 31 and 32, 33, which he along 100 the sides of the cylinder section 18 and communicate with the interior thereof through a plurality of nipples, as shown at 34. An additional supply of the solvent may be introduced through the shaft 13, which is 105 shown as tubular for this purpose and as

having eduction ports 35 opening to the cylinder section 18. The solvent is introduced into the tubular shaft through a branch pipe 36 in swiveled engagement with the end of 5 the shaft through a stuffing box 37. A plug 38 is placed within the bore of the shaft 13 beyond the cylinder section 18. The solvent together with the oils dissolved out of the material, escape from the cylinder section 18 10 through its eduction ports 39 in its walls, into the tank 19.

A screen 40 is preferably placed across the chamber of the tank 19 below the cylinder and may be provided with one or more 15 cups, as 41, from the bottom of which drain-pipes 42 lead to the exterior of the tank and are provided with valves, as 43, supplying means for testing the operation of the apparatus. The liquid contents of the tank 20 19 may be drained off through a pipe 44.

As the material passes on from the cylinder section 18, it holds by absorption some of the solvent, and this is evaporated out of it within the cylinder section 21 located 25 within the tank 22. For this purpose steam is introduced into the cylinder section 21 by means of a pipe 45 leading from a suitable source of steam pressure and entering the tank 22 through the branches 46, 47, which 30 discharge into the cylinder through pipes which may be constructed and arranged like the pipes 30 to 33 and which are therefore not shown in detail in the drawings. An additional supply of steam may be delivered 35 to the cylinder section 21 through the shaft 18, a steam pipe 48 being in swiveled engagement with the end thereof through a stuffing box 49. The hot steam causes the evaporation of the liquid held by the material, the vapors escaping through the eduction ports 50 of the cylinder section 21 into the tank 22, from which they may escape 40 through a pipe 51 which leads to a suitable condenser (not shown). Any liquids dripping 45 from the cylinder section 21 or resulting from condensation of the vapors within the tank 22, are retained by this tank and may be discharged therefrom through a suitable pipe, as 52. Passing beyond the cylinder section 21 the material reaches the discharge nipple 12. The rate of discharge of the material may be regulated by means of a valve 53 slidably mounted on the shaft 13 and movable toward and away from the 50 end of the cylinder, a lever 54 providing means for shifting this valve.

When the apparatus is used for treating garbage or other material normally containing moisture and which has not been 60 previously thoroughly dried out, the receiving end of the cylinder 10 may be inclosed within a steam jacket 55 to which steam is led through a suitable pipe 56 and from which water of condensation may be dis- 65 charged through a suitable pipe 57, the

vapors driven off of the material by this application of heat finding their escape through an opening, as 68.

The operation of the apparatus is as follows: The material admitted into the cylinder 10 through the hopper 11 is advanced by the spiral conveyer 17 to the cylinder section 18, at the receiving end of which it becomes impacted and forms a sufficiently solid mass to prevent the escape of the solvent therethrough. The spiral conveyer 21 detaches the material from the forward end of the plug thus formed and moves it on through the cylinder section 18 as a loose and open mass into which the solvent may readily pass, and delivers it into that portion of the cylinder between the sections 18 and 21 within which there is located no conveyer. There it again becomes impacted and forms a plug through which the solvent 85 will not flow, and also prevents the steam with which the material is next treated from passing backwardly into the cylinder section 18. The conveyer 23 detaches the material from this impacted mass and moves 90 it forward through the cylinder section 21 in a sufficiently loose condition to permit the passage into it of the steam there introduced for the purpose of eliminating the solvent and oils which may have been held 95 by absorption. As the conveyer 23 terminates short of the delivery end of the cylinder, the material again becomes impacted to a sufficient extent to prevent any loss of vapors, and the density of the plug here 100 formed may be regulated by means of the valve 53. It may be found desirable to provide means for choking the cylinder passage at each side of the section 18 for the purpose of more densely impacting the material to 105 prevent the escape therethrough of vapors and liquids, and when such choking is found to be necessary we employ truncated sleeves 69, 70, as shown in Fig. 1, but prefer to employ an elastically-expansible device such as 110 that illustrated in Fig. 5 of the drawings. This device comprises a number of tapering slats or staves 58 arranged in annular series and hinged, as shown at 59, to a collar 60 which may be clamped between the flanges, 115 as 61, 62, uniting the sections of the cylinder. The slats or staves 58 project from the collar 60 in the direction in which the material is moved, and their free ends are closed together by any suitable spring mechanism, as shown, by means of springs 63 coiled upon rods 64, which bear upon the slats or staves 58 and project outwardly through caps 65 attached to the outer surface of the cylinder, the springs reacting 125 between the ends of the caps and collars, as 66, on the rods. A sight gage 67 is shown as applied to the tank 19 to indicate the level of the liquid contents therein.

In treating the material with steam in the 130

cylinder section 21, it becomes moistened and must usually be dried before shipped as fertilizer. The apparatus may be provided with means for completing this last step so that when discharged therefrom it will be ready for packing, as in sacks, without further manipulation. To accomplish this purpose the end portion of the cylinder, that is to say, the portion lying between the section 21 and the discharge nipple 12, may be steam-jacketed, as shown at 71, in Fig. 6. For the purpose of carrying off any vapors which may accumulate within the tank 19, a valve-controlled pipe 72 leads therefrom to the pipe 52; and for the purpose of expelling from the tank 22 any vapors which may remain therein after the operation of the apparatus has been stopped, a steam pipe 73 may be led to the chamber thereof.

20 The method of extracting oils from solids as herein described may be practiced by other means than the apparatus forming the subject of this application, and such method is made the subject of our co-pending application Serial No. 541,202.

We claim as our invention:

1. In an apparatus for recovering oils from solids, in combination, a tubular cylinder a section thereof having foraminous walls, means for impacting material at each extremity of such section and for advancing material therethrough, and means for introducing an oil solvent into the material while within such section.
2. In an apparatus for recovering oils from solids, in combination, a tubular cylinder a section thereof having foraminous walls, conveying mechanism for advancing material through the cylinder, such mechanism being interrupted at each extremity of the named section, and means for introducing an oil solvent into said section.
3. In an apparatus for recovering oils from solids, in combination, a tubular cylinder having a section with foraminous walls, a section delivering to and a section leading from such first-named section, a conveyer within each section, the several conveyers being spaced apart, and means for introducing an oil solvent into the first-named section.
4. In an apparatus for recovering oils from solids, in combination, a tubular cylinder having a section with foraminous walls, a section delivering to and a section leading from such first-named section, a conveyer within each section, the several conveyers being spaced apart, and pipes communicating with the first named section through a plurality of nipples.
5. In an apparatus for recovering oils from solids, in combination, a tubular cylinder having a section with foraminous walls, a section delivering to and a section leading from such first named section, a conveyer

within each section, the several conveyers being spaced apart, a receiving hopper discharging into the delivery section, and means for introducing an oil solvent into the first named section.

6. In an apparatus for recovering oil from solids, in combination, a tubular cylinder having a section with foraminous walls, a section delivering to and a section leading from such first named section, a conveyer within each section, the several conveyers being spaced apart, a tubular shaft on which the several conveyer sections are mounted and having outlets to the first named cylinder section, and a pipe delivering to the bore of the shaft.

7. In an apparatus for recovering oils from solids, in combination, a tubular cylinder having a section with foraminous walls, a section delivering to and a section leading from such first named section, a conveyer within each section, the several conveyers being spaced apart, a tubular shaft on which the several conveyer sections are mounted and having outlets to the first named cylinder section, a pipe delivering to the bore of the shaft, and pipes delivering through the walls of the first named cylinder by means of a plurality of nipples.

8. In an apparatus for recovering oils from solids, in combination, a tubular cylinder a section thereof having foraminous walls, means for impacting material at each extremity of such section and for advancing material therethrough, means for introducing an oil solvent into the material while within such section, and a tank inclosing such cylinder section.

9. In an apparatus for recovering oils from solids, in combination, a tubular cylinder, two separated sections of which have foraminous walls, means for impacting material at each extremity of each such sections and for advancing material therethrough, means for introducing an oil solvent into one of such sections, and means for introducing a vaporizing agent into the other of said sections.

10. In an apparatus for recovering oils from solids, in combination, a tubular cylinder, two separated sections of which have foraminous walls, a shaft on the axis of the cylinder, and being tubular from each end to one of the named cylinder sections and having a plurality of lateral apertures opening thereto, pipes leading to each end of the shaft, and means actuated by the shaft for advancing material through the cylinder, such advancing means being interrupted at each end of each of the named cylinder sections.

11. In an apparatus for recovering oils from solids, in combination, a tubular cylinder, two separated sections of which have foraminous walls, a shaft on the axis of the

cylinder, and being tubular from each end to one of the named cylinder sections and having a plurality of lateral apertures opening thereto, pipes leading to each end 5 of the shaft, means actuated by the shaft for advancing material through the cylinder, such advancing means being interrupted at each end of each of the named cylinder sections, and a tank inclosing each of the 10 named cylinder sections.

12. In an apparatus for recovering oils from solids, in combination, a tubular cylinder, a section thereof having foraminous walls, the cylinder chamber being contracted 15 adjacent each extremity of such named section, means for introducing an oil solvent into such section, and means for advancing material through the cylinder.

13. In an apparatus for recovering oils 20 from solids, in combination, a tubular cylinder, two separated sections of which have foraminous walls and the chamber of which is contracted at each end of each of such sections, means for advancing material 25 through the cylinder, means for introducing an oil solvent into one of such cylinder sections, and means for introducing a vaporizing agent into the other of said sections.

14. In an apparatus for recovering oils 30 from solids, in combination, a hollow cylinder comprising a steam jacketed receiving section, and a section having foraminous walls, means for advancing material 35 through the cylinder and for impacting it at each end of the second named section, and means for introducing an oil solvent into said section.

15. In an apparatus for recovering oils

from solids, in combination, a tubular cylinder 40 having foraminous walls, means for advancing material through the cylinder, means for impacting such material at each end of such cylinder, and means for introducing a fluid into the cylinder for acting 45 upon the material contained therein.

16. In an apparatus for recovering oils from solids, in combination, a tubular cylinder 50 having foraminous walls, means for advancing material through the cylinder, means for impacting the material at the receiving end of the cylinder, a valve for restricting the discharge of material from the cylinder, and means for introducing a fluid into the cylinder to act on the material contained therein.

17. In an apparatus for recovering oils from solids, in combination, a plurality of chambers arranged in series, means for advancing material through the several chambers and for impacting it at the outlet of each chamber, and means for introducing an oil solvent into one of the intermediate 60 chambers.

18. In an apparatus for recovering oils 65 from solids, in combination, a chamber having a drain aperture, means for delivering material to such chamber and impacting it at the inlet thereto, means for introducing an oil solvent into the chamber, means for impacting the material at the outlet of the chamber, and means for delivering the material through such outlet.
